US0D1059948S

(12) **United States Design Patent** (10) **Patent No.:** **US D1,059,948 S**
(45) **Date of Patent:** **** Feb. 4, 2025**

(54) **SPOUT FOR A BOTTLE**

(71) Applicant: **NINGBO CHEFSHERE KITCHEN TECHNOLOGY CO., LTD.**, Ningbo (CN)

(72) Inventor: **Guoping Zhang**, Ningbo (CN)

(**) Term: **15 Years**

(21) Appl. No.: **35/519,837**

(22) Filed: **Dec. 26, 2023**

(80) **Hague Agreement Data**

Int. Filing Date: **Dec. 26, 2023**

Int. Reg. No.: **DM/234575**

Int. Reg. Date: **Dec. 26, 2023**

Int. Reg. Pub. Date: **Jan. 26, 2024**

(30) **Foreign Application Priority Data**

Aug. 30, 2023 (CN) 202330560333.X
